UNITED STATES PATENT OFFICE.

JENNINGS SCOTT McCOMB, OF DOBBS FERRY, NEW YORK.

DESK ATTACHMENT.

No. 873,770.

Specification of Letters Patent.

Patented Dec. 17, 1907.

Application filed March 8, 1907. Serial No. 361,196.

To all whom it may concern:

Be it known that I, JENNINGS SCOTT McCOMB, a citizen of the United States, and resident of Dobbs Ferry, in the county of Westchester and State of New York, have made certain new and useful Improvements in Desk Attachments, of which the following is a specification, taken in connection with the accompanying drawings.

10 This invention relates to desk attachments and relates especially to attachments for roll top office desks by which a special top or table is provided of suitable height for use when a person is standing, such top being suitable for book-keeping and other purposes and being arranged so as to fold up and be securely inclosed in a suitable casing when not in use.

20 In the accompanying drawings showing an illustrative form of this invention and in which the same reference numeral refers to similar parts in the several figures, Figure 1 is a side view of a desk showing the attachment in operative position, the casing and 25 the closure for said casing being shown in section. Fig. 2 is a side section showing the attachment inclosed in the case. Fig. 3 is a partial detail showing the collapsing of the leg and support; and Fig. 4 is a front view.

30 In the illustrative embodiment of this invention shown in the drawings, a desk of the general roll-top type is indicated having the top 26 to which the side pieces 1 are secured so as to properly support the desk cap 2, as is 35 usual. The casing 4 which is part of the attachment is secured upon the cap and firmly held in position by a depending flange 28 at the back of the casing which passes behind the rear edge of the cap and by suitable fastenings, which may be in the form of pivoted

40 buttons 27 adapted to engage the front edge of this cap member. The casing as indicated may be provided with the door 6 having the handle 9 and secured by the hinge 7 to the

45 flap 5, a section of the top of the casing of the desired width being secured thereto by the hinge 8 which may extend throughout the entire width of the casing if desired. The base 3 of the casing is preferably provided

50 with suitable guides which may be in the form of slotted metal plates 10 as indicated, to properly engage and support the reduced necks of the studs 11 secured to the top section 12 of the table 13. The table is also

55 preferably provided with a lower section or leaf 17 which may have a retaining ledge 18,

this leaf being secured to the main portion of the table by a suitable heavy hinge 14 which may extend its entire width, if desired, and which operates to rigidly support the table 60 sections in proper position when extended as indicated in Fig. 1.

The lower end of the table may be supported by legs 19 secured thereto by the pivots 20 and connected at their lower ends by 65 the rod 22 whose ends may project slightly beyond the outer surfaces of the legs. The supports 21 are preferably pivoted by the pins 29 to the legs adjacent their lower ends and may be provided with suitable slots 23 to 70 accommodate the ends of the rod 22, these slots having preferably a generally curved contour as indicated and being of sufficient depth to extend through to the outer face of the support, although this is not necessary in 75 all cases. Adjacent the lower ends of the supports they are rigidly connected by the stay 24, their lower ends being preferably provided with suitable cushioning material in the form of tips 25.

80 In the extended position indicated in Fig. 1, the table is firmly supported at its lower edge by the legs and supports which are prevented from buckling outward by the engagement of the ends of the rod 22 with the 85 slots 23, the upper portion of the table being supported by the rigid engagement of the heads of the studs 11 with the ends of the metallic guideways. The various portions of this attachment may, of course, be readily 90 folded together, the supports folding simultaneously about the corresponding leg members and the leg members folding upward against the leaf 17, a suitable spring clip 15 or other fastening being preferably provided 95 to engage the rod 22 and hold the parts in the closed position indicated in Figs. 2 and 3. The leaf 17 may thereupon be folded backward under the table 13 so that the parts may all be pushed within the casing, the 100 studs 11 moving backward along the slotted guides so that all the parts are completely inclosed within the casing 4 when the door 6 is closed as indicated in Fig. 2. The provision of suitable handles or straps 16 adjacent 105 the lower end of the table allows the convenient withdrawal of the parts from the casing when it is desired to use them.

Having described this invention in connection with an illustrative embodiment 110 thereof, to the details of which disclosure it is, of course, not to be limited, what is

claimed as new and what is desired to be secured by Letters Patent is set forth in the appended claims.

1. In desk attachments for roll top desks, 5 a casing provided with a depending rear flange and with pivoted buttons adjacent the front edge thereof to engage the edges of a desk cap and secure said casing thereto, said casing being provided with metallic 10 guideways on the bottom of the same adjacent each end thereof and with a hinged door and flap covering the front thereof, a table provided with depending headed studs 15 engaging said guides, a leaf hinged to said table and provided with a ledge and a spring clip, legs pivoted to said table leaf and connected at their lower portion with a rod having ends projecting through said legs, supports pivoted to said legs and provided with 20 slots co-operating with the ends of said rod and having tips, and a connecting stay adjacent their lower ends, whereby said table and supporting members may be operatively supported from said casing and inclosed 25 therein when in collapsed form.
2. In desk attachments, a casing having means to secure the same to the cap of a desk and provided with a door and with guides, a table provided with depending 30 studs engaging said guides and having a leaf hinged thereto, legs pivoted to said leaf and connected at their lower portions, and supports pivoted to said legs and provided with tips whereby said table and supporting 35 members may be operatively supported from said casing and inclosed therein when in collapsed form.

3. In desk attachments, a removable casing provided with means for holding it in alignment with respect to the desk cap, said 40 casing being provided with guides, a table provided with means engaging said guides, a leaf hinged to said table, and pivoted supporting legs on said leaf to support said table from a desk top and to allow the sectional 45 table and connected parts to be stored in said casing when in collapsed form.

4. In desk attachments, a removable member provided with guides, a table having members co-operating with said guides, 50 and supporting means movably secured to said table to support the same from the top of the desk and to allow said table to be moved rearward out of operative position when not in use.

5. A desk attachment for roll top desks, comprising a removable casing to fit upon the cap of the desk, means for removably holding the casing to the desk and a table normally inclosed within the casing but 60 adapted to be withdrawn from it and supported above the top of the desk.

6. A desk attachment for roll top desks comprising a removable casing having a flange and adjustable means to removably 65 secure the casing to the cap of the desk and a table normally inclosed within the casing but adapted to be withdrawn therefrom and supported above the top of the desk.
